UNITED STATES PATENT OFFICE.

JESSE E. GODLEY AND JOHN M. CARROLL, OF VALLEJO, CALIFORNIA, ASSIGNORS TO SPERRY FLOUR COMPANY, OF SAN FRANCISCO, CALIFORNIA, A CORPORATION OF CALIFORNIA.

BOX-STRAPPING MACHINE.

1,130,160.

Specification of Letters Patent.

Patented Mar. 2, 1915.

Application filed March 23, 1914. Serial No. 826,530.

To all whom it may concern:

Be it known that we, JESSE E. GODLEY and JOHN M. CARROLL, citizens of the United States, residing at Vallejo, in the county of 5 Solano and State of California, have invented new and useful Improvements in Box-Strapping Machines, of which the following is a specification.

This invention relates to improvements in 10 box strapping machines.

The objects of the invention are, first, to provide a simple, substantial, easily operated machine which is so constructed that it may be quickly adjusted to handle boxes of 15 various lengths and diameters, and second, to provide means for applying bands to the boxes under high tension and perfect alignment.

Further objects will hereinafter appear.

20 The invention consists of the parts and the construction and combination of parts as hereinafter more fully described and claimed, having reference to the accompanying drawings in which—

25 Figure 1 is a plan view of the machine. Fig. 2 is a longitudinal, vertical section on line 2—2, Fig. 1. Fig. 3 is a cross section on line 3—3, Fig. 2. Fig. 4 is a cross section on line 4—4, Fig. 2. Fig. 5 is a perspective of the band-gripping mechanism.

30 Referring to the drawings, A indicates the main frame of the machine in which the several parts of the box strapping mechanism are mounted.

35 B indicates a box supporting frame, and 2 a pair of standards on the upper ends of which are journaled a pair of band or strap-carrying reels 3. The box supporting frame is here shown as consisting of a base-plate 4, mounted upon timbers 5, carried by a pair of cross-frames 6, extending between the sides of the main frame A, and adjustably supported in same as indicated at 7. The outer end of the base-plate 4 is slotted 40 as indicated at 8, for the purpose of permitting the adjustment of a pair of end brackets 9. These are secured in their adjusted position by any suitable means, or as here shown by bolts 10. The brackets 45 9 are engageable with the ends of the box, as indicated at 11, and are provided for the purpose of holding these in alinement with the several parts of the box strapping mechanism. The box is further held in position 50 by a standard 12, suitably secured as at 13

to the supporting timber of the base-plate. The vertical adjustment of the base-plate permitted by the slotted cross-frames 6, permits the frame to be raised or lowered to handle boxes of different diameters, and the 60 adjustment of the crosswise frame of brackets 9 permits boxes of various lengths to be handled.

14 indicates a shaft which is journaled as at 15 in boxes supported on the upper side 65 of the main supporting frame. Suitably secured to said shaft is a pair of upwardly extending arms 16, upon the upper ends of which are formed sleeve extensions 17. On the outer ends of said sleeve extensions are 70 formed a pair of vertically disposed lugs 18 and supplementary lugs 19. Suitably secured between said lugs is a pivot pin 20, one end of which is sufficiently extended to form a support for a spring 21. Pivotaly 75 mounted on pins 20, between the lugs 18 are a pair of strap grips 22. The upper ends of said strap grips are connected by a cross-bar 23, and the rocking movement of the grips is limited by bars 24 extending 80 between supplementary lugs 19. Springs 21 carried by the inner projections of pins 20 are engageable at one end with sleeve extensions 17 and the upper ends with cross-bar 23, and are provided for the purpose 85 of normally holding the strap-gripping members in engagement with stop-bars 24. The lower ends of the strap-gripping members are cam-shaped as indicated at 25, and are so positioned as to become engageable 90 with a pair of shoes 26 carried on sleeves 17 between the vertical lugs 18. Arms 16 are secured to shaft 14 by screws 14^a, and are therefore adapted to be moved inwardly or downwardly on said shaft with relation to 95 the center of the machine. The cross-bar 23 extending through the upper ends of the strap-gripping members is similarly secured by said screws 23^a, and the second cross-bar 27 extending through the sleeves 17 on the 100 upper ends of arms 16 is also secured in this manner by screws 17^a. The adjustable mounting of the arms with connected parts permits these to be extended or contracted 105 as the case may be, for the purpose of strapping boxes of different lengths.

Standards 2 upon which the strap carrying reels 3 are mounted are adjustably secured to the main frame. This is accomplished by providing a pair of dove-tailed 110

guide members 28, having slots 29 formed therein. The base portion of the standards is grooved to engage the dove-tailed slots and are secured thereto by bolts 30, which are adapted to extend through slots 29, formed in the dove-tailed extensions previously described.

The whole mechanism so far described is operated through the medium of a foot-treadle which consists of a pair of arms 31, pivotally mounted on the cross shaft 32. The outer ends of said arms are connected by a foot-board 33, and extending across the arms upon brackets 34 is a cross-bar 35. Suitably secured to said cross-bar is a flexible cable 36 which passes through the guide sheave 37, the other end of said cable being secured as at 38 to approximately the center of cross-bar 23. The foot treadle is normally held in the elevated position indicated in Fig. 2 by reason of a coil spring 39 and arms 16 upon which the strap-gripping mechanism is normally held in the full line position indicated in Fig. 2, by means of a coil spring 40 which is attached at one end to the main arm and at the other to a downwardly extending arm 41, secured as at 42, to shaft 14.

The operation of the device will be as follows: The box to be strapped is first placed upon the base-plate 4. The side brackets 9 are then adjusted so as to engage with the ends of the box indicated in Fig. 1. The base-plate 4 is then either elevated or lowered as the case may be through the adjusting mechanism, indicated at 7 until the top of the box is slightly above the position of the strap-gripping mechanism, as indicated in Fig. 2. The box thus adjusted in position is then ready for the application of the straps, and this is accomplished as follows: The ends of the straps are first unwound from the reels 3 and passed through the vertical lugs 18 between the shoes 26 and the cam end 25 of the grips. They are passed over the box and secured by nails 43. The moment the ends of the straps have become secured, as indicated at 43, it is necessary to place sufficient tension upon the strap iron 50 to bring this taut as possible over the edge of the box. This is accomplished by depressing the treadle lever 31. Movement is transmitted when treadle 31 is depressed through cable 36 to bar 38; and due to the bar 38 being connected with the strap-gripping members same will cause the parts to rock into the dotted line position indicated at 44, and cause the cam ends of same to move into gripping engagement with the straps 45 which pass over shoes 26. A further depression of the foot-treadle will then cause bar 38, with connected strap-gripping members, together with lever 16, to move into the dotted line position, indicated at 46; 60 the strap being secured between the cam ends

25 of the gripping members and the shoe 26 will thus be drawn taut over the edge of the box, and may then be nailed to the box. The foot-treadle 31 is now released, permitting spring 39 to return the treadle to the normal elevated position, giving the cable sufficient slack to permit spring 40 to return arms 16 to normal position, and also permitting springs 21 to rock bar 23 with connected gripping members into released position. 70 The box is then turned over in the direction of arrow *a* to present a new side to be strapped. The cycle of operation; that is, that of depressing the foot-lever, again rocks the gripping members into gripping position, and draws the straps taut over the edge of the box. The moment the straps have been drawn taut the straps are nailed to the box, the foot-lever is then raised and the box is again turned. These operations are 80 repeated until the strap has become entirely wound around the box, when they may be severed and the box removed.

The machine construction as here shown relieves the operator of the necessity of 90 tightening the straps by hand. By simply pressing the foot-lever the straps are drawn much tighter than could be otherwise done. The operator is thus free to use both hands for the purpose of nailing the strap when 95 this is in taut condition. The adjustable mounting of the several parts, together with the guiding of the strap iron, insures perfect alinement of the straps upon the ends of the box. The nails by which the straps are 100 secured will thus always enter the end sections of the box, or in other words, prevent nails from entering the interior of the box where they might damage the goods contained therein, or any lining with which the 105 goods might be inclosed.

The machine is simple and compact in construction, and can be operated by any person. It may furthermore be adjusted to handle practically any size box and the 110 alinement of the strap iron produce a net of uniform result.

The materials and finish of the several parts of the invention may be such as the judgment and experience of the manufacturer may dictate.

Having thus described our invention, what we claim and desire to secure by Letters Patent is—

1. In a box-strapping machine, in combination, with strap-wound reels, a vertically disposed carrier having a pair of pivoted arms, spring means to tension the arms, a cross bar connecting the arms, a shoe on each arm, a vertical strap grip pivoted to each arm and having a cam on its lower end which cooperates with the shoe of the arm, springs connected to the grips and to the respective arms to normally hold the cams of the grips away from the shoes, a cross-bar 125

connecting the upper ends of the grips, a treadle, and a cable connected to the cross-bar of the grips and movably engaged with a stationary point to the rear of the arms and 5 connected to the treadle.

2. In a box-strapping machine, in combination, with a box support and strap-wound reels, a vertically disposed carrier swingable at its upper end toward and away 10 from the box, rigid jaws on the carrier, vertically disposed spring tensioned jaws pivoted to the carrier and having their lower ends for coöperation with the rigid jaws to grip the straps therebetween, means connecting the pivoted jaws to effect movement of same in unison, a cable connected to said connecting means of the pivoted jaws for moving the pivoted jaws to gripping position and for simultaneously swinging the carrier horizontally to draw the straps taut, and means operable 15 from the front side of the box support to actuate the cable.

3. In a box-strapping machine, in combination, with a box support and strap-wound reels, a vertically disposed spring tensioned carrier swingable at its upper end 20 to draw the straps taut.

toward and away from the box, and located 25 on the rear side of the box support, rigid jaws on the carrier, vertically disposed spring tensioned jaws pivoted to the carrier and having their lower ends for coöperation with the rigid jaws to grip the straps therebetween, means connecting the pivoted jaws to effect movement of same in unison, a cable connected to said connecting means of the pivoted jaws for moving the pivoted jaws to gripping position and for simultaneously swinging the carrier horizontally to draw the straps taut, and means operable 30 from the front side of the box support to actuate the cable.

In testimony whereof we have hereunto 40 set our hands in the presence of two subscribing witnesses.

JESSE E. GODLEY.
JOHN M. CARROLL.
